UNITED STATES PATENT OFFICE.

ALBERT A. DAY, OF NEW YORK, N. Y.

APPARATUS FOR PREPARING AND FEEDING FUEL.

SPECIFICATION forming part of Letters Patent No. 657,399, dated September 4, 1900.

Application filed May 2, 1900. Serial No. 15,264. (No model.)

To all whom it may concern:

Be it known that I, ALBERT A. DAY, a citizen of the United States, residing in the city of New York, (Brooklyn,) in the county of 5 Kings and State of New York, have invented certain new and useful Improvements in Apparatus for Preparing and Feeding Fuel; and I do hereby declare the following to be a full, clear, and exact description of the invention, 10 such as will enable others skilled in the art to which it appertains to make and use the same.

My present invention relates to apparatus for preparing and feeding fuel in a finely-divided condition to furnaces; and it consists 15 in certain novel features of construction and combination of parts, whereby improved results and great efficiency are obtained.

My said invention relates more particularly to the construction of the pulverizing-chamber and the devices connected and combined therewith, whereby certain new results are produced.

The best form in which I have contemplated embodying my said invention is illustrated 20 in the accompanying drawing, and the same is disclosed in the following description and claims.

In the drawing the figure is a plan view of the apparatus or pulverizing-chamber with 25 the upper portion removed, together with the parts connected thereto.

In said figure of drawing, A designates the casing of the pulverizing-chamber. The main portion of the casing is in the form of 30 an ellipse disposed in a horizontal position, having a part at each end removed to form plane terminations. At one end of this main body is the usual annular trough A', and at the opposite end is the breaking or grinding 35 mechanism B. This grinding mechanism is of any preferred form and is connected with the pulverizing-chamber for the purpose of delivering the fuel to the pulverizer after it has been acted upon by the breaking or grind- 40 ing mechanism.

C designates a horizontal shaft which passes centrally through the casing A and within which it is provided with fan or pulverizing blades c. Each of these blades is attached to 45 a shank c², which is inserted in a socket in the main blade-arms c³ and secured by a set-screw c⁴. By this construction the blades

can be readily adjusted radially to the desired distance from the interior of the casing, and the blades can also be adjusted angularly 55 in respect to the shaft C or the axis of the pulverizer.

In the drawing the blades c are all shown as set parallel to the shaft; but with varying conditions and kinds of fuel it may become 60 desirable to have one or more of the sets of blades at an angle to the shaft. Those nearest the fuel-inlet might be set so as to facilitate the forward movement of the fuel, and the blades nearest the exit might be set so as 65 to retard such movement, while those located centrally remain substantially parallel to the shaft.

Within the trough A' the shaft C is provided with the usual fan-blades c', as usual 70 in this class of devices, to withdraw the powdered or pulverized fuel from the pulverizer and deliver it to the furnace.

The inner surface of the casing A is throughout its entire length provided with a network 75 of slightly-projecting corrugations to hold and retard the unpulverized material, so as to enable the blades c to act more efficiently upon the same. The projecting portions of this roughened surface are raised above the 80 main portion of the surface but a short distance—from one-sixteenth of an inch upward, as may be found most desirable.

As the broken fuel comes from the grinder or breaker B it is acted upon by the first of 85 the pulverizing-blades, and the centrifugal action of the same throws this material outward against the inwardly-curving surface of the pulverizing-chamber A at this end of the same. The form of the chamber tends 90 to throw the material thus thrown against it toward the center of the pulverizer, where it is acted upon by the blades nearest the center of the chamber. The draft of air through the chamber induced by the fan-blades c' tends to draw all materials toward 95 the discharge end of the chamber; but when such materials come in contact with the inwardly-curving walls of the discharge end of chamber the inward curvature tends to retard and hold back the unpowdered or un- 100 pulverized portions of the fuel, which are effected by centrifugal action, so that they are kept from being discharged from the said pul-

verizing-chamber until they have been finely comminuted. The form of the chamber tends in the first place to prevent the return of the materials received from the grinder and also tends to prevent the too-free discharge of the unpulverized parts of the fuel.

It will be understood that the proportions of the pulverizer-chamber may be changed without departing from the spirit of my invention, so long as the principle of operation set forth is retained. For example, the said casing of said chamber may be made longer in proportion to its diameter or made shorter, and the amount of curvature given to the walls at the end may be varied.

What I claim, and desire to secure by Letters Patent, is—

1. In an apparatus for preparing and feeding fuel, the pulverizing-chamber having the general form of an ellipse and having an inlet at one end and a discharge at the opposite end as and for the purpose set forth.
2. In an apparatus for preparing and feeding fuel, the combination with the pulveriz-

ing-chamber having the general form of an ellipse and provided with an inlet at one end and a discharge at its opposite end, of revolving pulverizing-blades within said chamber adjustable radially and angularly in respect to the axis of said chamber, substantially as described.

3. In an apparatus for preparing and feeding fuel, the combination with the pulverizing-chamber of circular form, the diameter of which changes between its inlet and discharge end, of revolving pulverizing-blades within said chamber adjustable radially and angularly in respect to the axis of the chamber whereby the feed of the materials acted upon through the chamber may be regulated, substantially as described.

In testimony whereof I affix my signature in the presence of two witnesses.

ALBERT A. DAY.
